DRILL BIT LOOSENER

Samuel H. Malinak, Butte, Mont.

Application December 12, 1945, Serial No. 634,610

4 Claims. (Cl. 29—243)

1

This invention relates to a drill bit loosener, and particularly to a loosener by means of which bits of drills of the type used in coal mines may be loosened and removed for sharpening. The bits of drills used in coal mines and other specific forms of drills very often become wedged in the socket of the drill so tightly that it is very difficult to remove them, and it is therefore one object of the invention to provide a device by means of which a drill may be very firmly held and blows applied to the bit to dislodge it from the drill.

Another object of the invention is to so form the bit holder that a bit will be held in a horizontal position near the ground and in such relation to a pivotally mounted dislodging member is struck with a sledge hammer, blows will be delivered to the bit transversely thereof and in such manner that turning movement will be imparted to the bit and the bit worked loose from the socket of the drill into which it fits, better, faster and safer.

Another object of the invention is to provide the holder with a stationary jaw and a movable jaw movable toward and away from the stationary jaw by means of a member which is shiftable longitudinally by means of an actuating lever, the longitudinally movable member being formed with a sloping surface contacting with the movable member so that, as the movable member or bar is shifted longitudinally, the movable jaw will be shifted toward the stationary jaw.

Another object of the invention is to provide a device of this character which is very strong and capable of withstanding rough usage without being damaged.

The invention is illustrated in the accompanying drawing, wherein:

Figure 1 is a side elevation of the improved bit removing device,

Figure 2 is a top plan view thereof,

Figure 3 is a side view of one of the jaws for engaging a drill,

Figure 4 is a side view of the bit engaging member, and

Figure 5 is a perspective view of a mounting member for the bit engaging member.

This improved bit remover is employed for removing bits from drills used in rock drills such as are used in mines and quarries. These bits become tightly stuck in the drill after they have been used for some time, and when a workman attempts to loosen them by striking them with a hammer, it is difficult to do so and in addition very often small pieces of steel will be broken from a bit and a workman will be injured

by a spark or small particle of hot steel lodging in his eye. This cannot occur when the improved bit remover is used, since the bit will be placed in a horizontal position close to the ground and the workman stands in an upright position and uses a sledge hammer while dislodging the bit from the drill.

The body portion 1 of the bit remover has a base 2 carrying an upstanding web 3, along the upper edge of which is a head 4, and upon referring to Figures 1 and 2, it will be seen that the body has the same construction as a railroad rail and, in fact, is preferably formed from a portion of a discarded railroad rail. The base 2 of the body is secured upon a thick board 5 by fasteners such as spikes 6, it being understood that while the foundation 5 preferably consists of a board into which spikes are driven, it may be formed of metal and bolts or other suitable fasteners used for securing the body 1 upon it near one end. A portion of the head 4 is cut out to form a slot 7 substantially midway the length of the head and at opposite sides of this slot the head is cut to form recesses 8 and 9 which are flush with a side face of the web 3 of the body and constitute seats to receive a stationary jaw 10 and a movable jaw 11. The two jaws fit flat against the web of the body and are secured by bolts 12 and 13 and each jaw has its edge face presented toward the slot 7 formed with teeth 10a and 11a so that a drill set in place between the jaws may be very firmly gripped and prevented from slipping or turning after it has been gripped by the jaws. The opening in the jaw 10 through which the bolt 12 passes may be circular and of such diameter that it will snugly receive the bolt 12, but the opening 14 formed in the jaw 11 must be elongated transversely of the jaw so that this jaw may be slid transversely from the retracted position shown in Figure 2 toward the jaw 10 to an extended position in which it moves partially across the slot 7 and cause a drill to be very firmly gripped between the two jaws. The jaw 10 may also be formed with an opening elongated transversely of the jaw if so desired and thus allow either jaw to be used as a movable jaw when assembling the device. Before the bolts are applied, a metal strip 15 is disposed longitudinally of the body against outer side faces of the two jaws, and when the nuts of the bolts are tightened this strip or plate 15 will serve very effectively to hold the jaws in the recesses and guide sliding movement of the movable jaw toward and away from the stationary jaw.

When the bit of a drill is to be removed, the

drill is placed longitudinally of the foundation 5 with the end carrying the bit seated in the slot 1 between the two jaws and its other end resting upon the upper edge of the upstanding flange 16 of a strip of angle metal 17 which is secured upon the upper face of the foundation 5 transversely thereof by bolts or equivalent fasteners 18.

A bar 19 extends longitudinally of the foundation with its forward end portion passing through aligned slots formed in the strip 15 and the web 16 of the body 1, and since the side edge 20 of the forward portion of this bar extends diagonally, it constitutes a cam surface for engaging the movable jaw and forcing the movable jaw to an extended or gripping position when the bar is shifted forwardly. The rear end portion of the bar 19 is formed with forks 21 which are spaced from each other transversely of the bar. These forks pass under a pin 22 which projects from the web 16 of the bar of angle metal 17. A lever 23 is pivotally mounted upon the pin 22 where it is held by a nut 24 and this lever has its forward end portion formed with a downwardly extending arm 25 perforated to receive a bolt 26. The bolt 26 is engaged through a selected set of opposed openings 27 formed through the forks 21 and a cotter key 28 then applied to prevent the bolt from accidentally slipping out of place through the forks and the arm of the lever. The openings 27 are spaced from each other longitudinally of the forks, thus allowing the bar 19 to be longitudinally adjusted in accordance with the necessary longitudinal movement of the bar to effect tight gripping engagement of the jaws with the drill. The rear portion of the lever is widened, as shown at 29 in Figure 2, so that after a drill has been set in place at rest upon the flange of the cross bar 17 with its front end portion disposed between the jaws, the workman may place a foot upon the widened end portion of the lever and apply downward pressure to swing the lever about its pivot 22 and shift the bar forwardly a sufficient distance to cause the drill to be firmly gripped between the two jaws.

The bit to be removed projects from the front end of the drill and this bit passes through a recess 30 formed transversely in a bit engaging member 31. This bit engaging member or block extends vertically and at the lower end of the recess 30 is formed with a tongue 32 which projects transversely from the bit engaging member and will extend under the bit. An opening 33 is formed through the lower end of the bit engaging member or block 31 to receive the threaded stem 34 of a rocker bar 35. This rocker bar extends longitudinally of the body 1 at the opposite side of the web from the jaws 10 and 11 and midway its length is formed with a sleeve 36 through which the bolt 13 passes to pivotally mount the rocker bar. A spring 37, which has its lower end anchored to a clip 38 fixed to the base 2 of the body 1 by a screw 39, has its upper end engaged through an opening 40 formed through the rear end of the rocker bar so that the front end of the rocker bar and the block 31 will be urged upwardly and the tongue 32 and the bottom of the recess 30 held in engagement with the portion of the bit passing through the recess. After the drill has been secured between the jaws with its bit extending through the recess 30 and resting upon the tongue 32, the workman stands over the holder and strikes the front side face of the upper portion of the block with a sledge hammer. This causes the block or bit engaging member

to be tilted rearwardly and swung downwardly, and also causes the rocker bar 35 to be tilted about the bolt 13 and its forward portion swung downwardly so that, as blows are struck, jarring impacts will be applied to the bit and also twisting motion imparted to it. The bit will thus be loosened from the drill and may then be easily removed. Since the spring 37 is expanded each time the rocker bar is tilted about the bolt 13 and then contracts, the rocker bar will be rocked toward its initial position after each blow delivered by the sledge hammer. In view of the fact that the workman is in a standing position and strikes the block or bit engaging member with a sledge hammer having a long handle, there will be no danger of sparks flying from the bit or the bit engaging member lodging in the workman's eye. After the bit has been loosened and withdrawn from the drill, the lever 23 is swung upwardly to withdraw the bar 19 and thus release the movable jaw so that it may be shifted away from the stationary jaw and the drill be removed. The device may then be put away until again needed.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having thus described the invention, what is claimed is:

1. A device for removing a drill bit comprising a foundation, a body mounted upon said foundation and having a base and a web extending upwardly from the base and a head extending along the top of the web and projecting transversely therefrom, said head being formed intermediate its length with a transversely extending slot and at one side of the web being formed with recesses leading from the slot longitudinally of the head, jaws disposed vertically against the web with upper portions in the recesses, a strip extending between said jaws and across outer side faces thereof, bolts passing through end portions of said strip and through openings in the jaws and through the web, the bolt receiving opening of the movable jaw being elongated transversely thereof to permit movement of the movable jaw toward and away from the stationary jaw, a rocker bar pivotally mounted upon the bolt passing through the movable jaw at the opposite side of the web from the movable jaw, said rocker bar extending longitudinally of said body and having a front end portion bent to form a stem projecting laterally from the body, a block pivotally mounted upon said stem and extending upwardly therefrom and formed with a recess extending transversely thereof and with a tongue extending laterally from the block flush with the bottom of the recess, a spring engaging the rear end of the rocker bar for tilting the rocker bar about its pivot, and urging the forward end of the rocker bar and the block upwardly, and means for moving the movable jaw toward the stationary jaw to grip a drill disposed between the jaw and through the slot of the body and hold the drill firmly in place with a bit of the drill extending through the recess of said block.
2. A drill bit removing device comprising a foundation, a body mounted upon said foundation

and having an upstanding web and a head along the upper edge of the web projecting laterally therefrom, said head being formed intermediate its length with a slot and with recesses leading from the slot longitudinally of a projecting portion of the head, jaws disposed vertically against the web with their upper portions in the recesses, one jaw being a stationary jaw and the other being movable toward and away from the stationary jaw into and out of a gripping position, a rocker bar extending longitudinally of said body and pivotally mounted at the other side of the web from the jaws, said rocker bar having a front end portion formed with a stem projecting laterally from the web, a bit engaging member pivoted upon said stem and projecting upwardly therefrom and formed with a transversely extending recess and with a tongue projecting laterally from the bit engaging member at the bottom of the recess, spring means yieldably holding the rocker bar in a normal position and resisting downward movement of the forward end portion of the rocker bar, and means for moving the movable jaw toward the stationary jaw for gripping a drill and firmly holding the drill between the jaws with a bit of the drill extending through the recess of the bit engaging member, whereby blows may be delivered to the upper portion of the bit engaging member to dislodge the bit from the drill.

3. A drill bit removing device comprising a base, a body carried by said base and formed with a passage for receiving a portion of a drill and with recesses leading from the passage at opposite sides thereof, jaws in said recesses, one jaw being movable toward and away from the other into and out of a gripping position, a rocker bar pivoted to said body opposite the jaws and having one end provided with a stem projecting laterally from the body, a bit engaging member pivotally mounted upon said stem and projecting upwardly therefrom and formed with a bit receiving recess whereby, upon striking the upper portion of the bit receiving member, a bit engaged thereby will be dislodged from a drill gripped between the

45

jaws, and means for moving the movable jaw into position for gripping a drill between the jaws.

4. A drill bit removing device comprising a foundation, a body mounted upon said foundation and formed with a passage intermediate the width of the foundation for receiving a drill, jaws at opposite sides of said passage, one jaw being movable toward and away from the other jaw into and out of a gripping position, a rocker bar pivotally mounted at the other side of the body from the jaws, a bit engaging member pivoted to said rocker bar in position for engaging a bit transversely thereof and loosen the bit when blows are struck against the bit engaging member, a bar of angle metal mounted across said foundation in longitudinally spaced relation to said body, a flange of the angle bar being disposed vertically and having a stem projecting from one end, a lever pivoted upon the stem of said bar and having a downwardly extending front end portion, and a bar pivoted to the downwardly extending end of said lever and extending longitudinally of said foundation with its free end portion slidably passing through the body and formed along one side edge with a cam surface engaging the movable jaw to shift the movable jaw to a gripping position when the bar is shifted longitudinally of the foundation toward the body.
